Albert Granger, of New York, N.Y.
Letters Patent No. 1747, dated Apr. 21. 1863.

The schedule referred to in these Letters Patent and making part of the same.

To all whom it may concern:

Be it known that I, Albert Granger, of the City and State of New York, have invented a new and improved design for a steel pen ornamentation; and I do hereby declare that the following is a full, and exact description of said design.

The new feature as compared with any other steel pens now manufactured, is the impression on the heel of the pen, of a head in baso relief, the same being a likeness of Washington - incircled by two sprigs of laurel crossed at the base, or below the head, and ascending on either side, and meeting at the top, forming thereby a medallion.

What I claim as my invention, and desire to secure by letters patent is, the device impressed on the pen, namely a head of Washington incircled by a laurel wreath or two laurel sprigs so formed as to create a medallion, as shown and described.

Witness my hand in the matter of application for Patent on New Medallion Pen Design.

Witness.

R. H. Stillwell.
Henry Palmer.
